BLEEDING INSTRUMENT

Alfred E. Erickson, Charlotte, Mich.

Application May 8, 1945, Serial No. 592,546

2 Claims. (Cl. 128—275)

This invention relates to an instrument or tool for taking samples of blood from animals such as cattle for testing.

In taking samples of blood from cattle it is customary to puncture the jugular vein by means of a tubular-needle and to withdraw a sample of blood through the needle into a bottle. The puncturing of the vein should be done as quickly and painlessly as possible.

A frequently encountered difficulty in puncturing the vein is that pressure applied to it in inserting the needle causes it to flatten so that the needle may pass through both sides of the vein. Another difficulty is that the vein may slip while the needle is being inserted so that the needle does not strike the vein squarely.

These difficulties are avoided in accordance with the present invention by providing an instrument which thrusts the needle quickly into the vein and avoids the application of pressure which may cause the vein to slip or flatten. The sudden thrust of the needle is also less painful to the animal than the relatively slow manual insertion of the needle and less likely to give rise to difficulty in dealing with the animal.

Further objects of my invention are to provide an instrument for taking samples of blood from animals which can be used quickly in succession on a plurality of animals, it being necessary only to replace the filled bottle containing a sample of blood from one animal by a clean empty bottle, recock the needle and proceed to the next animal.

The invention is illustrated in the accompanying drawing in which

Fig. 1 is a front elevated view of the instrument, cocked and ready for use;

Fig. 2 is a similar view of the instrument showing the needle in the position which it occupies in use;

Fig. 3 is an end view looking down upon the instrument as seen in Fig. 1;

Fig. 4 is an end view of the instrument with the needle holder in position to release the needle;

Fig. 5 is a section on the line 5—5 of Fig. 2; and

Fig. 6 is a front elevational view of the needle. The instrument consists of the rigid frame 1 shaped to fit a person's hand. The frame 1 is generally oblong in shape, about 4 to 5 inches long and 1 to 2 inches wide. The drawing illustrates an embodiment of the instrument in full size. The frame may be made of metal or other suitably strong material. The frame is provided with the finger loop 2 which may be integral with the frame and serves not only as a convenient

means for carrying the instrument but also as a guard for the trigger 3 and to hold the trigger in place. Integral with or secured to the frame 1 are the open spring loops or clips 4 adapted to receive and hold the sample bottle 5. In line with the bottle 5 and integral with or suitably secured to the frame is the needle guide which consists of the straight portion 6 in line with the bottle and the two laterally projecting portions 7 and 8 each provided with a notch 9 for receiving and guiding the needle in its longitudinal movement. The trigger 3 consists of the two portions 10 and 11 at a small angle to each other and the two ends 12 and 13 which extend laterally substantially at right angles to the portions 10 and 11 through openings in the frame. The trigger is held in place by the end of the finger loop 2 bearing loosely against the trigger at the junction of the portions 10 and 11 and thus holding the ends 12 and 13 within the holes in the frame. It will be seen that the trigger is adapted to tilt from the position shown in Fig. 1 in which the portion 10 lies against the frame and the end 12 extends through the frame and serves as a trigger latch 14 for the member 15, to the position shown in Fig. 2 in which the portion 11 lies against the frame and the end 12 is retracted to release the member 14. This tilting movement is effected by the pressure of the fingers of the operator.

The rod 15 is slidably supported in openings in the ends of the frame 1 and carries on its upper end, outside of the frame, the laterally extending portion 16, the free end of which carries, or is shaped to form the needle holder 17. The needle holder as appears in Figs. 1 and 4 comprises two spaced apart parallel walls adapted to engage the opposite ends of the lug 18 on the needle 19. These two parallel walls of the needle holder are provided with aligned notches 20 adapted to fit around the needle.

The rod 15 also carries the thumb piece 14 which serves to turn the rod 15 and the needle holder against the torsional tension of the spring 21 from its position as shown in Figs. 1, 2 and 3 to its position as shown in Fig. 4 to release the needle. The thumb piece serves also as a means for applying pressure to move the rod 15 lengthwise of the frame against the longitudinal pressure of the spring 21 from the position shown in Fig. 2 to the position shown in Fig. 1 to cock the instrument. The thumb piece 14 further serves to engage the end 12 of the trigger 3 to hold the instrument in cocked position. One end of the spring 21 is fastened to the frame 1 and the other end to the thumb piece and is twisted

slightly so that it tends to rotate the rod 15, thumb piece 14, end 16 and needle holder 17 counter-clockwise as viewed in Fig. 4 so as to hold the needle firmly in the guide notches 9. Spring 21 also serves, upon release of the trigger 3 to project the needle with considerable force from its retracted or rest position shown in Fig. 1 to its extended or operative position shown in Fig. 2.

The short spring 22 serves merely to cushion the upward movement of the rod 15 and the parts which move with it when it is released from the position shown in Fig. 1 by movement of the trigger 3.

The operation of the instrument is as follows:

With the parts in the position shown in Fig. 1 the vein of the animal from which blood is to be taken is located, the point of the needle placed against the skin of the animal over the vein and the trigger 3 released by squeezing on the portion 11 of the trigger with the finger which occupies the finger loop 2. The spring 21 thrusts the needle forward to the position shown in Fig. 2 into the vein, blood flows from the vein through the needle and fills the bottle 5 and the needle is withdrawn by pulling the entire instrument away from the animal. The needle holder 17 is retracted to the position shown in Fig. 4, the needle removed from the notches 9 and the bottle 5 removed from the holders 4. A new bottle is inserted in the holders, needle 19 or a clean needle put back in the notches 9, the holder 17 brought down over the lug 18 and the instrument cocked to the position shown in Fig. 1 and is ready for a repetition of the described procedure.

I appreciate that the mechanical details of the instrument are capable of considerable variation and modification within the scope of my invention as defined in the appended claims. For example the bottle 5 might be shortened so that the needle 19, in its forward position, clears the bottle and permits the bottle to be removed and replaced without removing the needle.

I claim:

1. A bleeding instrument comprising a frame,

10 a rod slidably and rotatably supported on said frame, resilient means tending to move said rod longitudinally and to rotate the rod with respect to the frame, a latch for holding said rod in one position against the tension of the resilient means, a needle guide on said frame, means on said rod for engaging a needle carried by said guide and moving the same along said guide with longitudinal movement of said rod and means for rotating the rod against the tension of said resilient means to disengage the needle.

15 2. A bleeding instrument comprising an oblong frame adapted to be held in the hand, means at one side of the frame for releasably holding a tubular receptacle within the frame with its open end adjacent the front end of the frame, a needle supporting guide supported by said front end of the frame comprising at least two aligned notches adapted to receive the needle and permit longitudinal sliding movement thereof, said notches being in alignment with said receptacle, 20 a rod slidably and rotatably supported endwise of the frame, a spring connected to said rod and tensioned against the frame to urge the rod endwise of the frame toward said front end thereof, said spring being tensioned to rotate said rod, means on said rod for moving the same endwise away from the front end of the frame against the tension of the spring, a latch for 25 releasably securing the rod in the last named position, a trigger for releasing said latch to permit the rod to snap forward under the tension of the spring, an arm extending laterally from said rod outside said frame and adjacent the front end thereof, fingers on the free end of said arm for engaging a needle supported in said needle guide, a rectilinear tubular needle adapted to rest in said needle guide and a lug on said needle adapted to be engaged by said fingers and 30 to move said needle longitudinally of said guide with longitudinal movement of said rod, said means on said rod for moving the same longitudinally serving also as means for rotating the rod against the tension of the spring to release the 35 needle from said fingers.

ALFRED E. ERICKSON.
